DOW B. HUGHES, OF CLEVELAND, OHIO, ASSIGNOR, BY MESNE ASSIGNMENTS, TO
MOTOR IGNITION & DEVICES COMPANY, A CORPORATION OF WEST VIRGINIA.

IGNITION SYSTEM.

1,389,646.

Specification of Letters Patent. Patented Sept. 6, 1921.

Application filed April 2, 1910. Serial No. 553,111.

To all whom it may concern:

Be it known that I, Dow B. HUGHES, a citizen of the United States, residing at Cleveland, in the county of Cuyahoga and State of Ohio, have invented a certain new and useful Improvement in Ignition Systems, of which the following is a full, clear, and exact description.

This invention relates to the ignition systems for explosive or internal combustion engines.

One of the objects of the invention is to provide an ignition system which has a very high efficiency and will cause complete or total ignition of the explosive charge contained in the cylinder of an engine.

A further object is to provide a system which is more economical in the electric energy or wattage expended in establishing an igniting arc, than the systems employed heretofore.

A still further object is to provide a system which is inexpensive and easy to assemble and maintain in good working condition, and which permits the use of a magneto which is wound for low voltages only and is otherwise simple in construction and inexpensive to manufacture.

In carrying out my invention, I provide a system including a source of current, preferably in the form of a magneto having a low voltage winding, and which is adapted to supply to the spark plug or plugs low voltage current which produces an arc of high heat value and of sufficient duration to secure complete or total ignition or combustion of the combustible charge. Under normal conditions, the voltage of this magneto is insufficient to establish the arc and therefore to obtain the arc at the generated voltage, I provide means for temporarily reducing the resistance of the air gap between the spark electrodes. This is preferably accomplished by supplying to the electrodes a current of high frequency and high voltage, this current forming an arc which is of low heat value but which reduces the resistance of the air gap to an extent such that an arc of high heat value may be established by the magneto.

In the preferred embodiment of my invention the magneto armature winding is permanently connected to the spark plugs and provision is also made for periodically forming a local or short circuit through a portion of the winding and then opening the same, for the purpose of charging and discharging a condenser which is utilized for generating high frequency currents. This is accomplished by a make and break device which is operated by the armature shaft and is connected to the armature winding in a manner such as to periodically complete the local or short circuit through a portion of the winding and then open the same and when opened serving as a spark gap device and thereby causing the condenser which is connected to the circuit to be charged and disruptively discharged with high frequency or rapidity so as to create a high frequency current of low amperage but high voltage.

By means of a high frequency or disruptive discharge coil the primary of which is connected to the condenser and the secondary of which is connected to the spark plug, a high frequency current is induced in the circuit of the spark plug so as to create the high frequency arc of low heat value which, as before stated, is followed up by the arc of high heat value due to the magneto current. In a system adapted for a multi-cylinder engine, the condenser may be connected to the movable member of a distributor which distributes the high frequency currents to different low reactance disruptive discharge coils corresponding to the different cylinders.

The invention may be further briefly summarized as consisting in certain novel combinations and arrangements of parts which will be described in the specification and set forth in the appended claims.

In the accompanying sheets of drawings, I have shown the preferred embodiment of my invention, the ignition system and the magneto which is employed therein being adapted for a four-cylinder four-cycle engine. In the drawings, Figure 1 is a vertical sectional view of the magneto, certain portions being shown diagrammatically or conventionally for the sake of clearness; Fig. 2 is an end view of the same with portions shown in section; and Fig. 3 is a diagrammatic view of the main parts of the ignition system.

The magneto includes permanent field magnets 10 of the ordinary two pole type, and an armature 11 which is supported on

shaft sections 12 and 13, and which is provided preferably with a single low voltage winding 14. At one end of the armature is a casing 15 which incloses a pair of collector rings 16 and 17 which are engaged by brushes 18 and 19 respectively, and at the opposite side of the machine is a casing 20 containing a pair of two-to-one reducing gears 21 and 22 for a distributor, and a casing 23 which incloses an insulated collector ring 24 mounted on the end of the shaft section 12 and engaged by a brush 25. Said casing 23 also incloses a make and break device, including a cam 26 which is mounted on the shaft section 12, a lever 27 which is pivoted on the interior of the casing and is adapted to be pressed by the cam into engagement with the stationary element 28 of the make and break device, this element 28 being connected to the brush 25 by a conductor 29.

The distributor includes a shaft 30 on which the gear 22 is mounted and which is provided at its outer end with a rotary distributing arm 31 adapted to successively engage a number of spaced contacts or segments 32, these segments and the arm 31 being inclosed within a suitable casing 33 mounted upon the gear casing 20. Supported on the pole pieces between the legs of the field magnets 10 within a suitable casing 34 is a condenser 35, one terminal of which is connected by a conductor 35^a to the brush 19 which engages the collector ring 17 and the other terminal of which is connected by a brush or contact member 35^b to the rotating arm 31 of the distributor.

One end of the armature winding 14 is grounded at 36 and the opposite end of the winding is connected to the collector ring 16 which is engaged by the brush 18. By referring to Fig. 3 it will be seen that the brush 18 is connected by conductor 37 to the different spark plugs 38, four of which are shown in the drawing. It may be here noted that by so connecting the spark plugs to the armature winding, the full voltage of the magneto is at all times impressed on the electrodes of the different spark plugs, but the voltage of the magneto is such that under ordinary conditions no arcs could be established at the spark plugs because of the resistances of the air gaps. In order, however, that arcs of high heat value may be established at the generated voltage, the resistances of the air gaps are reduced successively at the different plugs by impressing on the spark electrodes a high voltage and supplying to the same high frequency currents of very low amperage, which create arcs of low heat value. For this purpose, I bring out from some point 39 between the ends of the armature winding 14 a tap, and this I connect by a conductor 40 and by an insulated rod 41 extending through the shaft

section 12 which is hollow as shown, to the insulated collector ring 24, which as stated before, is engaged by a brush 25 electrically connected to the stationary element 28 of the make and break device.

The cam 26 of the make and break device is of the two point type, that is, at each half revolution of the magneto armature, it causes the closure of the make and break device. It will be seen, however, that each time the make and break device is closed a portion of the armature between the tap or point 39 and the ground point 36 is short circuited on itself, the short-circuit connections from the grounded point 36 including the section of the armature winding to the point 39 of the latter, the conductor 40, insulated rod 41, ring 24, brush 25, brush 28, lever 27 of the make and break device and the cam 26 which is grounded on the shaft section 12.

This circuit just described which for convenience of description may be termed the "local circuit" is connected by conductor 42 to the collector ring 17, which as stated before, is connected by brush 19 and conductor 35^a to one terminal of the condenser 35, the other terminal of which is connected to the rotary arm of the distributor. Therefore, each time the local circuit is closed, current is generated therein, and when it is opened, the condenser which as will appear is connected to ground, is charged and disruptively discharged with great rapidity, setting up in the condenser circuit a high frequency current of high voltage but extremely low and almost negligible amperage, the make and break device serving as a spark gap device across which the condenser is disruptively discharged.

In order that this high frequency current may be employed for creating arcs of low heat value in the air gaps of the spark plugs, I employ high frequency or disruptive discharge coils 43 each of low reactance or inductance, and one of which will be provided for each cylinder of the engine. Each of these coils 43 includes a primary winding 43^a, one terminal of which is grounded, and the other terminal of which is connected to one of the stationary contacts or segments 32 of the distributor, and each coil also includes a secondary winding 43^b connected to one of the spark plugs, each spark plug therefore having in its circuit the secondary of a disruptive discharge coil, the primary of which is connected to one of the segments 32 of the distributor. It will be understood that as the distributor arm is rotated, the primaries of the coils are successively connected in series with the condenser. The low reactance of the coils 43, is secured by employing coils of few turns and without iron cores.

The parts are so arranged and operated that when the poles of the armature sweep into the magnetic field of the magnet, and

in fact at each half revolution of the armature, with the parts constructed and arranged as here shown, the make and break device is closed, short circuiting a portion 5 of the winding so that a current is generated in this portion, and immediately after the short circuit is opened. When this occurs, the rotating arm of the distributor is in engagement with one of the contacts or seg-
 10 ments of the distributor grounding the condenser through the primary of one of the induction coils. The opening of the short circuit at this time causes the condenser to be charged and disruptively discharged with
 15 great rapidity so as to generate high frequency currents of high voltage, but of almost negligible amperage. The condenser or high frequency circuit does not include the magneto armature winding, for the rea-
 20 son that the condenser is disruptively discharged so as to produce a high frequency current across the terminals of a make and break device when the latter is opened, the make and break device therefore serving, when opened, as a spark gap device. A high frequency current is therefore induced in the secondary of the coil, and this induced high frequency current of high voltage and low amperage passes to ground through the
 25 spark plug, creating an arc of low heat value. This arc reduces the resistance of the air gap of the spark plug to an extent such that an arc of high heat value is established by the current of the magneto at the voltage
 30 generated therein, it being understood that when the arc of low heat value occurs, the armature is in a position such that the maximum voltage of the magneto is generated in the armature winding. This arc of high
 35 heat value which follows immediately after the arc of low heat value, is partly sustained or carried by the high frequency arc and continues at the spark plug until the armature poles sweep out of the magnetic field, or until the voltage drops from its maximum
 40 value to a value such that it is unable to maintain the arc. This arc is, however of sufficient duration to cause complete ignition of the charge in the cylinder. The arc
 45 of low heat value followed by an arc of high heat value occurs successively at the different spark plugs as the armature and distributor are rotated.

In this manner an arc of high heat value 55 and of sufficient duration is obtained with a small expenditure of electrical energy, as compared with the expenditure which takes place with the systems that are generally employed. At the same time, it is a very simple matter to wind the armature, inasmuch as there is only a single winding, and no high voltage insulation need be provided. The system is otherwise inexpensive to manufacture and assemble, and is very reli-
 60 able, particularly as there is little danger of
 65

the insulation being broken down or of a short-circuit accidentally taking place at any point.

It will be understood of course that my invention is not limited in its application to 70 ignition systems for any particular number of cylinders; it may be employed with advantage in any type of engine and with any number of cylinders.

I do not desire to be confined to the exact 75 details of arrangements shown, but aim in my claims to cover all modifications which do not involve a departure from the spirit and scope of my invention.

Having thus described my invention, what 80 I claim and desire to secure by Letters Patent is:

1. In an ignition system, spark electrodes, means for supplying to the electrodes high frequency current of high voltage so as to 85 form an arc of low heat value and for supplying to the electrodes a current at relatively low voltage so as to form an arc of high heat value which follows after the arc of low heat value, comprising a generator having an armature winding, means for forming a local short circuit for the armature winding and for opening the short circuit, a condenser and a disruptive discharge coil, the condenser being connected to 90 said circuit in series with the primary of the coil, and the electrodes being connected to the armature winding in series with the secondary of the coil.

2. In an ignition system, spark electrodes, 100 a generator connected to the electrodes, a make and break device, and connections between the latter and the winding of the generator for forming a short circuit for the winding and for interrupting the same, a 105 condenser connected to said circuit and generating a high frequency current at a high voltage when said circuit is closed and opened, and a disruptive discharge coil having a primary connected to said circuit 110 in series with the condenser and a secondary connected to the generator in series with the electrodes, whereby a high frequency current is induced in the electrode circuit causing an arc of low heat value to 115 be established.

3. In an ignition system, a plurality of spark plugs, a generator having an armature winding connected to the electrodes of the spark plugs so as to impress on the same 120 a voltage which is normally insufficient to form arcs at the same, and means for supplying high frequency currents to the electrodes of the spark plugs so as to reduce the resistances of the air gaps of the latter, comprising a make and break device, and connections between the latter and the armature winding for forming a local short circuit through the latter, a condenser, a distributor, said condenser having one terminal 125

connected to said circuit and the other terminal connected to the movable member of the distributor, and disruptive discharge coils having primaries connected to the stationary segments of the distributor, whereby they are alternately connected in series with the condenser and having secondaries each connected to the generator in series with one of the spark plugs.

10 4. An ignition system comprising a source of current, a spark plug, means receiving current from said source and producing an oscillatory discharge of high voltage, connections for subjecting the spark plug to the entire oscillatory discharge to initially establish a spark at the plug, and connections between the source and the spark plug through which current received from the source is supplied directly to the spark plug following the initially established spark.

15 5. An ignition system comprising a source of current, a spark plug, means receiving current from said source for producing a disruptive discharge of high voltage, connections for subjecting the spark plug to the entire disruptive discharge for initially establishing a spark at the spark plug, and other means for supplying current received

from the source to the spark plug following the initially established spark.

30

6. An ignition system for internal combustion engines comprising as a source of current a dynamo electric machine, a spark plug, means receiving current from said source to establish a spark at the spark plug, said means including a path in electrical circuit with said source for delivering current generated by said source through the spark plug after said spark has been established.

35

7. An ignition system comprising a source of current, a spark plug, means receiving current from said source for producing an oscillatory discharge to initially establish a spark to the spark plug, said means including a path in electrical circuit with said source for delivering current generated by said source through the spark plug following the initially established spark.

40

In testimony whereof, I hereunto affix my signature in the presence of two witnesses:
